UNITED STATES PATENT OFFICE.

JAMES T. HAMBAY, OF WILKINSBURG, PENNSYLVANIA.

SWITCH MECHANISM.

SPECIFICATION forming part of Letters Patent No. 399,888, dated March 19, 1889.

Application filed July 3, 1888. Serial No. 278,963. (No model.)

To all whom it may concern:

Be it known that I, JAMES T. HAMBAY, a citizen of the United States, residing at Wilkinsburg, in the county of Allegheny and State of Pennsylvania, have invented or discovered certain new and useful Improvements in Switch Mechanism, of which improvements the following is a specification.

The invention described herein relates to certain improvements in mechanism for shifting and locking switch-points, and has for its object a construction of mechanism whereby the unlocking, shifting, and subsequent locking of the points is effected by a single movement of the mechanism, and whereby such movements of the shifting mechanism and of the points is prevented during the passage of a train or car over the switch-points.

In general terms the invention consists in the construction and arrangement of mechanical devices, all as more fully hereinafter described and claimed.

In the accompanying drawings, forming a part of this specification, Figure 1 is a plan view of a portion of a railroad-switch and my improved mechanism applied thereto, and Fig. 2 is a sectional view of the switch shifting and locking mechanism on an enlarged scale.

Within convenient proximity of the movable switch-rails I secure a bed-plate, 1, in which is secured a pin or bolt, 2, having an enlarged head, 3, forming a journal for the toothed wheel, 4. This wheel is rotated by a rack, 5, held in engagement with the wheel by a friction-roller, 17, mounted on a pin secured to the bed-plate, said rack being connected by a bell-crank, 6, and rod 7 or other suitable devices to the operating mechanism.

(Not shown.) On the upper face of the wheel 4 is secured a pin, 8, which is connected by a link, 9, to the movable switch-rails and by a link, 10, to the locking-pin 11. This locking-pin 11 is arranged in suitable guides, 12, formed on the bed-plate 1, and is adapted to engage holes formed in the locking-bar 13, secured at one end to the movable switch-rails and passing through a guide-opening, 14, formed in the bed-plate transverse of the path of movement of the locking-pin. The locking-pin or

other suitable part of the mechanism 11 is connected by a rod, 15, to the detector-rail 16, located in suitable proximity to the switch-points, as shown in Fig. 1.

The operation of my improved mechanism is as follows, the several parts being in the position shown in Fig. 1: The rack-bar 5 is pushed inwardly by means of the bell-crank 6 and rod 7, thereby rotating the toothed wheel 4, as indicated by the arrow. During the movement of the pin 8 in said wheel from the position shown to the point *a* very little motion will be imparted to the switch-rails, but the locking-bolt 11, being arranged at right angles to the path of movement of the switch-rails and in line with said movement of the pin 8, will be entirely withdrawn from engagement with the locking-bar. As the pin 8 moves from the point *a* to the point *b*—*i. e.*, in line with the path of movement of the switch-rails—the latter will be shifted to the desired position; but the locking-pin will be only slightly moved, as such movement of the pin 8 from *a* to *b* is transverse to the path of movement of the locking-pin.

The distance between the points *a* and *b* is equal to the required movement of the movable switch-rails, and hence by the time the pin 8 reaches the point *b* said rails will have been shifted and the hole *e* in the locking-bar 13 brought into line with the locking-pin 11. The pin 8 in its further movement from the point *b* to the point *c* will be effective only in pushing the locking-pin into the hole *e*, thereby locking the switch-rails in position. Although the pin 8 in moving from its initial point to the point *a* and between the points *b* *c* will have a slight movement in the line of travel of the switch-rails, the resiliency of the connections will be sufficient to permit of such slight motion.

As the detector-rail is connected to the locking-pin in such manner that the rail is raised above the main rail by the unlocking movement of said pin, it follows that said pin cannot be withdrawn from the locking-bar while a car is standing on or passing along the portion of the main rail adjacent to the detector bar or rail.

In returning the movable switch-rails to

normal position the above-described movements of the operating mechanism are reversed, as will be readily understood.

It will be observed that the locking-pin and movable switch-rails are so connected to the operating-wheel that full movements are imparted to the pin and rails in sequence, and that a full movement of the locking-pin always precedes and follows the full movement of the rails, and that this proportioning of the movements of the locking-pin and rails can be effected either by connecting said parts to the wheel at the same or diametrically-opposite points, the direction of the locking and unlocking movements of the pin being reversed in the latter case.

It will also be observed that the locking-pin and the detector-rail are so connected to the wheel that the amount of movement of the wheel necessary to lower the detector-rail below the tread of the main rail will move the pin 8 a little past a line passing through the axis of the wheel and the pin connecting the link 9 to the switch-rails, so that any force applied to the rails tending to shift the same will tend to rotate the wheel in the direction of the locking movement of the pin. This relative arrangement of the parts prevents any accidental shifting of the switch-rails.

30 I claim herein as my invention—

1. In a switch mechanism, the combination of movable switch-rails, a locking-bar con-

nected thereto, a locking-pin, and a rotating wheel, the locking-pin and switch-rails having independent connections to the wheel at 35 the same or diametrically-opposite points, whereby a full movement of the pin preceding and succeeding a full movement of the switch-rails is secured, substantially as set forth.

2. In a switch mechanism, the combination of movable switch-rails, a locking-bar connected thereto, a locking-pin, and a rotating wheel, the locking-pin and switch-rails having connections to the same or diametrically-opposite points of the wheel, said connections being arranged at right angles to each other, 45 substantially as set forth.

3. In a switch mechanism, the combination of movable switch-rails, a locking-bar connected thereto, a locking-pin, a detector-rail, and a rotating wheel, the locking-pin, detector-rail, and switch-rails having connections to the same or diametrically-opposite points of the wheel, the connections for the detector-rail and locking-pin being arranged at right angles to the connection of the switch-rail, 55 substantially as set forth.

In testimony whereof I have hereunto set my hand.

JAMES T. HAMBAY.
